(57) **CLAIM**

The ornamental design for an ashtray device as shown and described.

DESCRIPTION

FIG. 1 is a top-back-right perspective view of an ashtray device;

FIG. 2 is a bottom-back-left perspective view of the ashtray device;

FIG. 3 is a top view of the ashtray device;

FIG. 4 is a back view of the ashtray device;

FIG. 5 is a bottom view of the ashtray device;

FIG. 6 is a left-side view of the ashtray device;

FIG. 7 is a right-side view of the ashtray device; and,

FIG. 8 is a front view of the ashtray device.

The broken lines in the drawings depict portions of the ashtray device that form no part of the claimed design.
